UNITED STATES PATENT OFFICE.

JOHN T. KEWISH, OF NEW YORK, N. Y., ASSIGNOR OF ONE-FOURTH TO JOHN C. GARAND, OF NEW YORK, N. Y.

MACHINE GUN.

Application filed July 9, 1918. Serial No. 243,047.

To all whom it may concern:

Be it known that I, JOHN T. KEWISH, a citizen of the United States, residing in the borough of Manhattan, in the city, county, and State of New York, have invented certain new and useful Improvements in Machine Guns, of which the following is a specification.

This invention relates to an improved machine gun of the type adapted to be carried on and fired from the shoulder of the user.

Certain objects and advantages of my invention are as follows:

First, as the principal object, to dispense with the recoil and gas operated mechanism as heretofore employed in automatic and machine guns, and to provide a light, simple and reliable machine gun comprising a few parts of simple construction which are easy to assemble and operate, and so designed and arranged that the power for actuating the automatic parts is taken from the primer of the cartridge when said cartridge is fired. Secondly, to provide a simple and reliable automatic mechanism which can be depended on to fire either single shots or by machine action as desired, independently of the skill of the operator.

Other objects of my invention are: to provide an automatic gun mechanism capable of machine action, in which the power actuating the automatic parts is derived from the primer of the cartridge, but in which means are provided to prevent the primer from coming completely out of the cartridge when fired; to provide a gun mechanism capable of machine action in which means are provided for securely locking the cartridge in the barrel of the gun; to provide a movable actuator piece through the movement of which and from its transmitted energy the gun is automatically unloaded and loaded; to provide an automatic movable breech mechanism which shall be spring-actuated in the closing direction, the weight of the movable breech parts being so proportioned to the stiffness and length of the spring that the rearward movement of the mechanism will store sufficient energy in the spring to reload the gun, return the mechanism to firing position and to fire the

cartridge; to provide an automatic gun mechanism capable of machine action which may be reliably used for sharp-shooting purposes; to provide an automatic gun mechanism capable of machine action in which a firing pin carried by the breech mechanism is held in mounted or cocked position after the breech mechanism is in firing position; to provide an automatic gun mechanism capable of machine action, in which the breech block is securely locked when the mechanism is in firing position; to provide an automatic gun mechanism capable of machine action in which the breech block is securely locked when the mechanism is in firing position and in which a firing pin carried by the breech is held in mounted or cocked position after the breech block is locked; to provide an automatic gun mechanism capable of either single shot or machine fire, in which the trigger mechanism is so arranged that when firing single shot the trigger must be let go after firing and pulled anew for each shot before the gun can fire; to provide an automatic gun mechanism capable of either single shot or machine fire in which the trigger mechanism can be positively and surely disabled as to machine action; to provide an automatic gun mechanism capable of either single shot or machine fire, in which machine action is obtained by holding the trigger in a different position from that in which it is when the piece is fired in single shot action; to provide novel means for mounting the sights; to provide a novel extractor mechanism; and to provide improved means for discharging the gas out of the line of sight.

A further object of my invention resides in the particular arrangement and combination of parts hereinafter described.

The preferred embodiment of my invention is shown in the drawing accompanying and forming a part of this specification, and the invention will readily be understood from a description of this drawing.

In the drawing,

Fig. 1 is a vertical sectional view, parts being, however, in elevation, of the portion of a gun according to my invention extending forward from a transverse plane through

the firing pin, the parts being in fired position.

Fig. 1^A is a vertical sectional view, parts being shown in elevation, of the portion of the gun shown in Fig. 1 which lies to the rear of a transverse plane extending through the firing pin, the parts being in fired position. The magazine is omitted from Figs. 1 and 1^A.

10 Fig. 2 is a view similar to Fig. 1, except that the operating mechanism is shown in horizontal section.

Fig. 3 is a sectional view on the line 3—3 of Fig. 1.

15 Fig. 4 is a sectional view on the line 4—4 of Fig. 1.

Fig. 5 is a sectional view on the line 5—5 of Fig. 1.

20 Fig. 6 is a sectional view on the line 6—6 of Fig. 1.

Fig. 7 is a vertical sectional view showing the operating mechanisms of the piece in the positions occupied when a fresh cartridge is being inserted. It also shows the 25 magazine in position.

Fig. 8 is a detailed view of the trigger mechanism and also shown the arrangement employed for holding the magazine in position.

30 Fig. 9 is a detailed view of a bolt employed for holding the trigger mechanism, and also the stock, in position. It is the final bolt employed in assembling the piece.

35 Fig. 10 is a detail view showing the receiver in longitudinal section.

Fig. 11 is a detail view showing the stock bracket.

40 Fig. 12 is a detail longitudinal sectional view through the rear end of the cartridge chamber and forward end of the breech mechanism of my gun, showing the relation of the parts immediately after the firing of the cartridge and illustrating the amount of movement permitted the primer in the 45 cartridge. This view also illustrates my gun as used with a special form of primer having relatively thick and long side walls.

50 Fig. 13 is a detail sectional view taken on a line parallel to and immediately below the line of Fig. 2.

Fig. 14 is an elevational view of the casting or receiver in which the automatic parts of my gun are mounted.

55 Fig. 15 is a view of my rear sight as it appears when looking from the rear or right hand side of Figs. 7 and 14.

Fig. 16 is a top plan view of my gun showing parts appearing also in Figs. 1 and 7.

60 Fig. 17 is an elevational view of the forward end of the actuator of my gun.

Fig. 18 is a side view of the actuator shown in Fig. 17.

65 Fig. 19 is a rear view of said actuator, taken from the right of Fig. 18.

Fig. 20 is a longitudinal sectional view of a commonly used small arms cartridge in loaded condition, illustrating the relative size and position of the primer.

Fig. 21 is a view of the rear sight when 70 elevated and adjusted for its greatest range, taken when looking from the rear of the gun.

In my improved machine gun, the power which actuates it is derived from the primer 75 of the cartridge. The gas pressure generated in the cartridge moves the primer back a short distance, thus transmitting power to a tappet or movable part which in turn transmits the movement or energy to an actuator. The actuator then moves back in the receiver of the gun, and operates first to unlock the bolt, moving some distance in doing this before the same is fully unlocked. This allows time for the gas to escape from 80 the barrel before the bolt is withdrawn, and provides a margin of safety against backfire, and in case a bullet lodges in the barrel. As the actuator continues to move backwards, it carries the bolt and its lock with 85 it, the bolt lock travelling on guideways in the receiver. The cartridge is extracted by an extractor carried on the bolt, and is ejected from the receiver by contact with an ejector situated in the receiver in such way 90 as to be moved in and out of position by a cam on the bolt. This movement backwards of the actuator, with its connected parts, compresses the main operating spring in the rear end of the receiver. After being 95 compressed to its utmost this spring sends forward again the actuator, with its connected parts, expanding itself until held back against the head of the firing pin, when said firing pin is detained on a pawl pivoted in the receiver, from whence the firing pin mounts on to a catch on the actuator. Said pawl is then lifted from the firing pin by a cam on the actuator which 100 operates as the actuator moves forward by the impetus received from the spring. The spring thus being freed again pushes the actuator ahead with the firing pin cocked on the catch on the actuator, forcing the cartridge into the barrel by the bolt which the actuator pushes ahead. After the cartridge is in its place in the barrel, and the bolt in its most forward position, the actuator continues to move forward a short distance in forcing the bolt lock down into position on the end of the bolt, and in front of the guideways in the receiver, by the action of cam surfaces, the bolt lock being held securely in place against the front of the guideways in the receiver. The gun is now ready to fire again, and the firing pin is sent forward to strike the primer by the same spring which brought the whole breech-block ahead, it being pressed against the head of the firing pin when this pin was 105

detained on the pawl and moved to the catch, and still pressed there when the firing pin was mounted and brought to its position to fire. The firing is then done, either in single shots or by machine action, as desired.

The single shot and machine action are both controlled by a single trigger and associated mechanism, the one action or the other being determined by the position to which the trigger may be pulled when firing, the machine action occurring when the trigger is in its rearmost position. When firing single shots, the trigger is positively held from being pulled back to the machine fire position by a stop, which can be moved out of the way when desired. In single shot firing, a pivoted catch on the trigger mechanism engages the catch on the actuator to pull the latter down and release the firing pin. These two catches are so arranged that the trigger must be let go after firing and pulled anew for each shot before the gun can fire. Consequently, there is a marked line between shots fired by pulling the trigger each time and the machine action. The user can make no mistake, and reliable single shot firing can be obtained without special skill or training. The single fire trigger arrangement, in combination with the bolt and lock therefor also ensures perfect aim and steady fire, as the cartridge must be locked securely in firing position before the cocked firing pin can be let go. However, after each discharge the gun is automatically set for the next shot and the speed is determined by the will of the user within wide limits, and so long as there is a cartridge in the magazine.

When it is desired to utilize the machine action, the stop previously mentioned is displaced from the path of the trigger in its rearward motion and the trigger is held in a position further back than the one in which it is fixed for firing single shots. When held in such position, the catch of the trigger mechanism is drawn down out of the way of the catch on the actuator, but the latter catch is automatically tripped to release the firing pin as the actuator goes home to its forward position by a cam member which is elevated by the trigger.

Suitable means are provided also for cocking the gun into position for the first shot and for securely locking the mechanism of the gun in a safety position, from which it cannot be fired. I provide also an improved arrangement for dissipating the gas and bending downwards the flash at the mouth of the gun, as well as a novel arrangement for mounting the sights. My invention will be more completely understood and further advantages will appear from the following detail description:

Referring in detail to the drawing, 1 des-

ignates the stock bracket secured to a stock 3 of any approved pattern by bolts 2, 4 and 5. 6 designates the receiver which is secured to the stock bracket by a horizontal T slot and lug joint 7 at the rear end and 70 by a slot and lug connection 8 at the front end. In mounting the stock bracket on the receiver, the stock bracket is brought into engagement with the receiver so that the T slot 7 in the receiver engages the lug 9 75 on the stock bracket, and so that the lug and slot 8 are in position; then by turning the bolt 10 (see Fig. 9) the receiver and stock bracket are locked firmly in position. The barrel 11 is secured to the receiver by 80 the screw-thread connection as shown. The magazine is indicated at 12 and may be of any approved type adapted to automatically supply cartridges 13 in position to be engaged one at a time by the bolt 15 on its 85 forward movement and pushed into position in the barrel.

The mechanism for taking energy or power from the primer and for automatically operating the piece comprises an actuator 14 mounted to a slide in guideways formed in the receiver as shown clearly in Fig. 4. This actuator has considerable mass, and as I will later explain operates to store up sufficient energy when the cartridge is fired to carry the mechanism through a complete cycle of operations. The bolt 15 is mounted free to slide in the slot 16 cut in the actuator 14 (see Fig. 4) 95 and has mounted on it and carries with it in its movement the extractor 17. The spindle 18 has a threaded connection at 19 with the actuator and extends into the bolt and maintains the bolt in position, free, however, to slide a certain amount on this spindle. 20 designates a tappet mounted in the forward end of the bolt in front of the spindle. This tappet is provided with a slot 21 adapted to receive a lug 22 on the extractor 17. The slot 21 is of such a length that the tappet can move forward until it is firmly pressed against the primer by the spindle 18, and thereafter when the cartridge is fired can move rearwardly with respect to the bolt a sufficient distance to store enough energy in the actuator and associated parts to operate the various mechanisms. Preferably the tappet is not permitted to move far enough to allow the primer to come out of the cartridge before the tappet is brought to rest, and I have demonstrated that sufficient energy can be stored up in this way to actuate the piece without allowing the primer to come out. After the tappet has moved the limited distance and has been brought to rest by lug 22 on the extractor 17, the actuator 14 and the spindle 18 continue to move rearwardly 110 so that the cam surface 23 on the actuator 115 comes in contact with the cam surface 24 120

on the lock 25 (see Fig. 7), this lock keeping bolt 15 fixed for an instant after the cartridge is fired. The contact of these two cam surfaces operates to move the lock upwardly into the position shown in Fig. 7. When the lock is thus raised it rises above the shoulders 26 on the guideways and is then free to move rearwardly with the actuator. The lock 25 has a T slot engagement 10 at 28 with the rear end of the bolt and carries the bolt rearwardly in order to extract and eject the cartridge. The extractor 17 as above explained has a lug 22 and this extends through a slot in the bolt as clearly 15 shown in Fig. 2, so that the extractor is forced to move with the bolt.

It will be seen that the firing pin is also thrown rearwardly by the primer at the same time as the actuator. The actuator, 20 firing pin, and associated parts, on their back movement compress the spring 29 and store sufficient energy in this spring so that the spring returns the movable parts to firing position, overcoming their friction, inserting a cartridge, locking the bolt to hold the cartridge firmly, and driving home the firing pin. I find that it is necessary, for 25 good results, that the reciprocating parts which receive energy from the primer should 30 have a certain minimum weight in order that they may accumulate sufficient energy to carry out the operations of ejecting the cartridge and inserting a fresh one and to overcome the friction of the parts in passing 35 through a cycle of operations. Also the spring must be capable of storing sufficient energy to return the reciprocating parts from their rearmost position to the firing position, to insert the fresh cartridge and to 40 drive the pin home in firing. I have found by experiment that good results are obtained when the actuator, pin and parts rigidly attached thereto weigh about one and three 45 fourths pounds, and the spring is of spring wire (.070 inches diameter) coiled into a helix about twelve inches long when un-compressed.

The small spring 30 is employed as a cushion 50 to insure the actuator coming to a stop when the cushion spring reaches the rear end 31 of the receiver. After the lock has been raised the actuator continues to move rearwardly compressing the spring 29, and when it moves rearwardly sufficiently far, 55 the rear end of the cartridge case strikes the point 32 of the ejector 33, and is thrown sharply to one side and out of the piece through the opening 200 in the receiver. It 60 will be noted that in the position shown in Fig. 2, the point 32 of the ejector is out of line with the rear end of the cartridge. In order to bring the point 32 in contact with the rear end of the cartridge case, a cam surface 34 fixed on the bolt is provided, and this 65 cam surface engages the corner 35 of the ejector

and tilts the ejector sufficiently to bring the point 32 in contact with the empty cartridge case as it moves rearwardly. The cam surface 36 on the bolt operates to engage the ejector and set it in the position shown in 70 Fig. 2 as the bolt moves forward. After the cartridge has been ejected, the actuator moves back until stopped by the cushion spring 30 engaging the rear wall 31. The actuator and associated parts carried therewith then move forward until the head 37 of the firing pin 75 engages the pawl 38, the rear end of which is normally held down so as to engage the head 37 as it moves forward. The pawl 38 stops the forward movement of the firing pin. The actuator continues to move forward until the cam surface 39 on the actuator engages the cam surface 40 on the pawl so as to lift it out of engagement with the head 80 of the firing pin. While the pawl 38 is detaining the head 37 of the firing pin, the catch 41 rises until its shoulder 42 engages the head of the firing pin and holds the firing pin in cocked position. This catch 41 is pivoted at 43 on the actuator and is actuated by a spring 44, so that it normally assumes a position to engage the head of the 85 firing pin. The bolt as it moves forward picks up the cartridge which has been moved in front of it by the spring 12^a of the magazine and pushes it into the chamber of the barrel. As the actuator moves forward the lock 25 comes in contact with the cam surface 45 formed on the top wall of the receiver 6 which operates by engaging the 90 surface 46 of the lock to push the lock bodily down enough to disengage the rear face 47 of the lock with the shoulder 48 on the actuator 14. Thereafter, as the actuator moves forward, the cam surface 49 on the 95 actuator engages the cam surface 50 on the lock and forces the lock down into locked position, against the front of the shoulders 26, that is to say, in the position shown in 100 Fig. 1. The surface 45 operates to prevent the lock moving forward and also brings the actuator to a stop. The mechanism now is in cocked and firing position.

It will be seen that, when the parts are in 105 cocked position, only the firing pin is mounted and hence there is a minimum of jar on discharge both in single shot and machine firing. My gun is consequently adapted for any use to which a hand rifle may be put, such as sharpshooting, etc.

The trigger mechanism consists of the trigger 51 pivoted at 52 to the bracket 53. The bracket is held in fixed position in the receiver by the bolt 5 above referred to, and the bolt 10 in Fig. 9. The forward end 54 of the trigger 51 engages the rear end of the lever 55 pivoted at 56 on the bracket 53. The rocking lever 55 is slotted and carries the catch 57 pivoted thereon at 58. A stop 59 for the trigger is provided in order that 110

the piece may be set to fire automatically or to fire single shots. The stop is set by a trip lever 60 and operates as I will later explain. When the trigger 51 is pulled, the catch 57 is pulled down compressing the spring 61 and the hook 62 on the catch 57 engages the hook 63 on the catch 41 and releases the firing pin which fires the cartridge and thus completes the cycle of operations when the piece is used to fire single shots. It will be seen, however, from Fig. 7 that, when catch 51 is in cocking position and the trigger is pulled back, catch 57 cannot make operative engagement with hook 63, so that the trigger must be released after each shot before another can be fired.

When it is desired to operate the piece automatically, the stop 59 is set in the position shown in dotted lines in Fig. 1 by an appropriate change in the position of cam member 60. Then when the trigger 51 is drawn back, it is free to move far enough to bring the cam 64 on the rocking lever 55 into position to engage the corner 65 of the catch 41, and automatically trips this catch as it moves forward. This surface 64 is so positioned that it trips the catch 41 slightly before the actuator comes to rest on its forward movement. When the parts are in this position the catch 57 is inoperative, being held down out of the way of the catch 41. The operation of the mechanism when used automatically is the same as when used to fire single shots, except as modified by the operation of cam surface 64.

The trigger 66 operates the pawl 67 which engages the notch 68 in the magazine so as to hold it in operative position. When it is desired to remove an exhausted magazine and insert a new one, the trigger 66 is moved forward bringing the pawl 67 out of the notch 68 so that the change of magazines can easily be made. The pawl 67 is normally held in engagement with the notch 68 by the pressure of the spring 61. A safety sear is shown at 69 and is pivoted by pin 70 on the receiver. When the handle of this safety sear is thrown forward from the position shown in Fig. 1, the sear engages the firing pin, locks the actuator by reason of its cylindrical portion 69^a contacting with the arcuate surface 14^a (Figs. 1 and 18) on the actuator, and operates as a lock to prevent the accidental firing of the piece. It also may be used to cock the firing pin since when it is thrown into safety position the shoulder 71 engages the head of the firing pin and forces it into cocked position as will be apparent from Fig. 1.

In order to position the first cartridge and to put the operating mechanism into cocked position, a hand-operated bolt 72 is provided and mounted to slide in the groove 73 on the receiver. A pawl 74 is mounted on this bolt and is positioned by a spring 75

so as to normally lock the bolt in forward position. When the bolt 72 is pulled back, the pawl 74 automatically releases and then swings far enough through the slot 80 in the receiver to engage the notch 76 in the actuator, and thus allow the actuator to be moved back compressing the spring and introducing the cartridge and cocking the piece and putting it into condition to fire the first cartridge. When the bolt reaches its back position, the rear wall of slot 80 or shoulder 77 on the receiver engages the end 78 on the pawl 74 and releases the actuator so that the actuator can move forward. The operator then moves the bolt back into the forward position where it is automatically locked by the pawl 74.

This bolt 72 is made long to allow for closing the slot 80 to keep dirt out.

Also the actuator is made long enough to normally close the opening in the receiver through which the shell is ejected for the same purpose.

As is well known, difficulty has been experienced in sighting automatic rifles owing to the flash and expansion of the hot gases at the end of the barrel. This difficulty has been partly cured by placing a sleeve at the end of the barrel of the general type shown at 81. I have found that the action of such sleeves is greatly improved if the outer end is deflected downwardly as indicated at 82. This arrangement discharges the gases in a stream which has time to cool and spread before reaching the line of sight.

It will be seen that member 81 carries the front sight, and I find that this arrangement enables me to place the front sight in the most advantageous position as regards use and at the same time to set the sight accurately with a minimum of trouble. In order to hold the sleeve or choke 81 securely and at same time insure that the sight shall not be turned out of line as might be the case if member 81 were secured by a threaded joint, I attach member 81 to the end of the barrel by a dovetail and pin connection, the pin being shown at 83. Moreover, to assist in adjusting the front sight 84, I form a dovetail connection shown at 85 between the sight and the standard 86, so that the sight can be readily adjusted transversely of the gun.

It will be seen that the detaining pawl 38 is mounted on the pin or bolt 87 (Fig. 3) and I find that this pin comes in the best position for mounting the rear sight 88 so that I can utilize said pin for both purposes. Moreover, by placing the rear sight as just indicated, I arrange it to co-operate with the receiver to excellent advantage.

As shown in Figs. 1, 7, 10, and 14, I cut the rear ends of the upstanding ribs or shoulders 89 to produce a downwardly and rearwardly sloping bevel 90. The sight 88

can be folded down between shoulders 89, and I have provided outwardly projecting ears 91 on the adjustable head 92 of the sight, said ears having edges arranged to engage the notches 99 on bevels 90. The height of this sight can thus be adjusted up to nine hundred yards by engaging the ears with the respective notches. If higher ranges than nine hundred yards are required, the sight is swung upwardly and forwardly somewhat beyond the ninety degree position and ranges above nine hundred yards obtained by adjusting head 92 as indicated, by graduations on one of the legs of the sight. I provide also a pawl 93 on head 92 which is for engaging notches on one of the legs to hold the head in vertically adjusted position. It will be seen that head 92 folds between the shoulders 89, only ears 91 projecting, so that pawl 93 is protected and the sight is not exposed to damage. Moreover, I provide a thumb-bolt 94 with associated spring for normally holding pawl 93 in engaging position, members 93 and 94 being so mounted in recesses in the side of head 92 as not to interfere with turning the sight down between shoulders 89. A bridge piece is provided between the outer ends of the legs and on said bridge piece is an outstanding lug 95 in which is a notch forming part of the battle sight. Immediately below said notch is a peephole 96 which is used for careful shooting when the sight as a whole is folded back. A peep-hole 97 is provided in head 92 for use when the sight is elevated. The spring 98, one end of which controls the detaining pawl 38 and the other end of which controls the safety member, is used also to maintain the sight either folded or raised as desired. For this purpose the rear end of said spring is cut to form three fingers, the centre one 98^b of which contacts with the detaining pawl, and the other two 98^a—98^c of which contact with the hubs on the inner ends of the legs of the rear sight. It will be seen that my principle of operating by power derived from movement of the primer is applicable to many types and sizes of gun using any desired form of cartridge, so long as a primer is used. Moreover, it will be understood that the power taken from the primer must be properly proportioned to the mechanism of the particular gun. It will be seen also, that the amount of power derivable from a given primer depends upon its length and diameter. My experiments have shown that the primers of the standard cartridges for small arms in use in the United States are so proportioned as to work my preferred mechanism herein described in a highly satisfactory manner. However, I contemplate using this principle on cartridges of various kinds and with mechanism requiring more

power in proportion to the cartridge than is the case with that shown and described herein. I also contemplate using power from the primer for performing certain functions in connection with the magazine, which are not possible with the form of magazine shown herein. Finally, it is advisable with certain types of gun to obtain a longer impulse than can be obtained with standard primers now in use. For these reasons, I have designed a special primer 300 as illustrated in Fig. 12 in association with my improved breech mechanism. This primer has its side walls 301 made relatively long in proportion to its diameter as compared to the standard U. S. small arms primer.

Moreover, the side walls 301 of my primer are made thicker than the head of the primer, so that the primer can move out of the cartridge a greater distance without danger of collapsing.

It will be understood that I have shown a standard form of a magazine in connection with my own improvements and said magazine is adapted to contain two rows or banks of cartridges of which only one appears in the drawing.

It will be understood that while I have shown and described herein the preferred embodiment of my invention, nevertheless I do not wish to be limited thereto, since many changes may be made in the form and arrangement of the parts without departing from the spirit of my invention. Moreover, parts of my invention may be used without using the whole.

Having thus described my invention, I claim:

1. A self-loading gun comprising, in combination, a bolt for holding the rear end of a cartridge to be fired, an actuator having a limited movement with respect to said bolt, a firing pin carried with and having a limited movement with respect to said actuator, means for urging said pin forward, means for retracting said pin with respect to said actuator, means carried on said actuator for retaining said pin in retracted position, and means whereby said firing pin may be released from said retaining means.

2. A self-loading gun comprising, in combination, a bolt for holding the rear end of a cartridge to be fired, an actuator having a limited movement with respect to said bolt, a firing pin carried with and having a limited movement with respect to said actuator, means for urging said pin forward, means for retracting said pin with respect to said actuator, means carried on said actuator for retaining said pin in retracted position, and means whereby said firing pin may be released from said retaining means either in single shot or rapid firing sequence, as desired.

3. In a device of the class described in

- combination, a casing, an actuating block slidably mounted in said casing, a bolt mounted in said block for holding a cartridge to be fired, said bolt and block being capable of a restricted relative movement, a spindle fixed to said block and projecting within said bolt, a firing pin mounted within said spindle, said pin and block being thrown rearwardly by the motion of the primer, a spring for returning said block and bolt, means for cocking said pin including a catch mounted on said block, and trigger mechanism adapted to release said catch.
4. In a device of the class described in combination, a casing, an actuating block slidably mounted in said casing, a bolt for holding a cartridge to be fired mounted in said block, said bolt and block being capable of a restricted relative movement, a spindle fixed to said block and projecting within said bolt, a firing pin mounted within said spindle, said pin and block being thrown rearwardly by the motion of the primer when the cartridge is fired, a spring for returning said block and bolt, means for cocking said pin including a catch mounted on said block, and trigger mechanism adapted to release said catch, said trigger mechanism comprising two releasing means, one operating only after being reset, and the other operating upon contact with the catch.
5. In a device of the class described in combination, a casing, an actuating block slidably mounted in said casing, a bolt for holding a cartridge to be fired mounted in said block, said bolt and block being capable of a restricted relative movement, a spindle fixed to said block and projecting within said bolt, a firing pin mounted within said spindle, a tappet piece surrounding the forward end of said pin within said bolt and having a limited rearward movement therein upon the firing of the cartridge whereby said block and pin are accelerated in a rearward direction, a spring for returning said block and bolt, means for cocking said pin including a catch mounted on said block, and trigger mechanism adapted to release said catch.
6. In a device of the class described in combination, a casing, an actuating block slidably mounted in said casing, a bolt for holding a cartridge to be fired mounted in said block, said bolt and block being capable of a restricted relative movement, a spindle fixed to said block and projecting within said bolt, a firing pin mounted within said spindle, said pin and block being thrown rearwardly by the motion of the primer, a spring for returning said block and bolt, means for cocking said pin including a catch mounted on said block, trigger mechanism adapted to release said catch, and a locking member for holding said bolt momentarily stationary after the firing of the cartridge.
7. In a device of the class described in combination, a casing, an actuating block slidably mounted in said casing, a bolt for holding a cartridge to be fired mounted in said block, said bolt and block being capable of a restricted relative movement, a spindle fixed to said block and projecting within said bolt, a firing pin mounted within said spindle, said pin and block being thrown rearwardly by the motion of the primer, a spring for returning said block and bolt, means for cocking said pin including a catch mounted on said block, trigger mechanism adapted to release said catch, and a locking member carried by said block for holding said bolt momentarily stationary after the firing of the cartridge.
8. In a gun, in combination, a breech mechanism comprising a reciprocating actuator, a firing pin mounted on and having a limited movement relatively to said actuator, a catch acting to hold said firing pin when in cocked position, said catch being pivoted intermediate its ends to said actuator, and trigger means whereby said catch may be operated to release said firing pin, said trigger means including a pivoted catch for co-operating with said first mentioned catch on one side of its pivot point and a cam for co-operating with said first mentioned catch on the other side of its pivot point to release said firing pin.
9. An automatic gun mechanism comprising in combination, a bolt for holding the cartridge firmly in firing position, said bolt leaving the primer free to move, a movable actuator, a firing pin carried on and movable relatively to said actuator and a lock for said bolt, said lock being free to move relatively to said bolt transversely of the barrel when said bolt is in locked position and being operated by the movement of said actuator.
10. An automatic gun mechanism comprising in combination, a reciprocating actuator, a bolt for holding the cartridge firmly in firing position, said bolt leaving the primer free to move and being mounted on said actuator, a firing pin carried on and movable relatively to said actuator, said bolt and actuator having a limited relative movement, and a locking piece having a grooved connection with said bolt and mounted to move transversely of the barrel while said bolt is locked and moving rearwardly with the bolt and actuator after the bolt is released, said actuator having means for moving said piece transversely of the gun to lock and unlock said bolt.
11. An automatic gun comprising in combination, reciprocating breech mechanism including a reciprocating firing pin having a head thereon, a main spring engaging said

head for actuating said breech mechanism in the forward direction, and a pawl for engaging said head on the forward travel of the breech mechanism and acting to momentarily detain said pin, said mechanism having suitable means for retaining said pin cocked in a relatively detained position as it moves forwardly.

12. An automatic gun comprising in combination reciprocating breech mechanism including a reciprocating firing pin having a head thereon, a main spring engaging said head for actuating said breech mechanism in the forward direction, and a pawl for 10 engaging said head on the forward travel of the breech mechanism and acting to momentarily detain said pin, said mechanism having a catch which automatically engages the head of said pin when it is retained by 15 said pawl.

13. An automatic gun comprising in combination a reciprocating breech mechanism including a firing pin, a pivoted member for momentarily detaining said pin on the 25 forward travel of said mechanism, a rear sight, and common means for mounting said pivoted member and said sight.

14. An automatic gun comprising in combination a reciprocating breech mechanism 30 including a breech block and a firing pin, a main spring for actuating said mechanism on its forward travel, and means for momentarily detaining said pin during its forward travel; said spring expanding until 35 stopped by the detention of said pin, then expanding further in putting the breech block into firing position, and expanding to its furthest position in driving said pin to fire the shot.

40 15. In a gun in combination, a reciprocating breech mechanism, a casing or receiver in which said mechanism is mounted, said receiver having a slot therein, a hand cocking device having a pawl adapted to extend through said slot to engage said breech mechanism to draw the same back, and means whereby said pawl is automatically released from said mechanism.

50 16. In a gun in combination, a reciprocating breech mechanism including a bolt and a locking piece therefor, a hand cocking device for said mechanism including a pawl and a receiver or casing for said mechanism, said receiver having a slot for said pawl, an exterior guideway for said device, an opening for the ejection of a cartridge, openings in the bottom for the assembling of the parts of said mechanism, a cam for engaging and bearing down said locking piece, and track guideways on which parts of said mechanism run, said guideways being so arranged that they become the thrust support for said bolt and locking piece when the bolt is locked in firing position.

65 17. In a gun in combination, a reciprocating

breech mechanism comprising a firing pin, and a safety locking device adapted to intervene between the firing pin and the remainder of said mechanism to force back and mount said pin and simultaneously to hold the remainder of said mechanism ahead.

18. An automatic gun mechanism comprising in combination, a reciprocatory actuator having a slot, a bolt mounted in 75 said actuator and having a lateral recess opening to said slot, and an extractor mounted in said slot and having a lug extending into said recess.

19. An automatic gun mechanism comprising in combination, a reciprocatory actuator having a slot therein a hollow bolt mounted on said actuator and having a lateral aperture opening into said slot, a tappet piece within said bolt and having a recess and an extractor mounted in the slot in 80 said actuator and having a lug extending through the aperture in said bolt and into said recess to limit the movement of 85 said tappet piece.

20. In a gun in combination, an automatic breech mechanism comprising a reciprocatory actuator receiving its energy from the discharge of the cartridge, a bolt and locking piece associated with said actuator, and reciprocating therewith, and a receiver or casing for said mechanism, said receiver having guideways for said mechanism, said guideways being so arranged with respect to said mechanism and said locking piece being automatically so actuated that said guideways become the thrust support for said bolt and locking piece when the bolt is locked in firing position.

100 21. An automatic gun comprising a receiver, a transverse pin thereon, an oscillatory detaining or cocking pawl pivoted on said pin, and a rear sight also pivoted on said pin.

110 22. In a device of the character described, in combination, an actuating block, a bolt carried by said actuator, a spindle fixed to said block and projecting into said bolt, a firing pin mounted within the spindle, a tappet positioned to contact with the primer and perforated to permit access of the firing pin to the latter, the tappet being so constructed as to limit the forward movement of the firing pin.

115 23. In a gun, a receiver or casing provided with a slot adapted for the reception of a pawl carried by a cocking slide, and with an exterior guideway for said slide, said guideway having an opening for the ejection of a cartridge shell, and said receiver having openings in the bottom for the assembly of the parts normally held in the receiver.

120 24. In a device of the character described,

in combination, an actuator, a bolt carried thereby, a slotted tappet carried by said bolt, and means extending into said slot and governing the movement of the tappet.

6 25. In a device of the class described, in combination, a bolt for holding a cartridge to be fired, a firing pin movably mounted

within the bolt, a spindle carrying the firing pin and projecting into said bolt, and a tappet limiting the forward movement of the 10 firing pin produced by said spindle and arranged to engage the primer so as to be moved rearwardly thereby.

JOHN T. KEWISH.
